CLAIM

The ornamental design for a fuel injector nozzle, as shown and described.

DESCRIPTION

FIG. 1 is a top perspective view of a first embodiment of a fuel injector nozzle;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a cross-sectional view thereof taken along line 8-8 shown in FIG. 1;

FIG. 9 is a cross-sectional view thereof taken along line 9-9 shown in FIG. 1;

FIG. 10 is a top perspective view of a second embodiment of a fuel injector nozzle;

FIG. 11 is a front view thereof;

FIG. 12 is a back view thereof;

FIG. 13 is a left-side view thereof;

FIG. 14 is a right-side view thereof;

FIG. 15 is a top view thereof;

FIG. 16 is a bottom view thereof;

FIG. 17 is a cross-sectional view thereof taken along line 17-17 shown in FIG. 10; and,

FIG. 18 is an enlarged view thereof.

The dashed broken lines depict portions of the fuel injector nozzle that form no part of the claimed design. The dot-dashed broken lines represent boundaries of the claimed fuel injector nozzle and form no part of the claimed design.

1 Claim, 18 Drawing Sheets
